UNITED STATES PATENT OFFICE.

SAMUEL CLELAND DAVIDSON, OF BELFAST, IRELAND.

INLET-OPENING OR EYE OF CENTRIFUGAL FANS OR PUMPS.

No. 820,399.

Specification of Letters Patent.

Patented May 15, 1906.

Application filed January 27, 1905. Serial No. 242,971.

To all whom it may concern:

Be it known that I, SAMUEL CLELAND DAVIDSON, a subject of the King of Great Britain and Ireland, and a resident of Sirocco Engineering Works, Belfast, Ireland, have invented certain new and useful Improvements in and Relating to the Inlet-Opening or Eye of Centrifugal Fans or Pumps, of which the following is a specification.

10 This invention relates to the inlet-opening or eye of centrifugal fans or pumps.

The invention is particularly applicable to centrifugal fans or pumps of the type illustrated in Patent No. 662,395, granted to me 15 on November 27, 1900, which relates to a fan-wheel having numerous elongated blades arranged in drum form, so as to inclose within them a relatively large and substantially unobstructed intake-chamber. In a pending 20 application, Serial No. 229,896, filed October 25, 1904, I have illustrated certain improvements which are especially applicable to this type of fan, the preferred construction therein shown comprising a fan-wheel having 25 blades which are shorter than the depth of the casing and an eye formed with an inwardly-extended throat disposed eccentrically to the fan-wheel shaft. The present invention relates to an improved construction 30 of such eye and throat, and while especially adapted for use with fans of the construction above referred to is applicable to various other types of centrifugal fans.

According to this invention I employ an 35 eye or inlet-opening with a throat extended within the fan-casing. The inward termination of said throat, which may be circular or non-circular, (but preferably circular,) is eccentric to the axis of the fan's rotation, and 40 the entrance to said throat is of larger dimensions than the inner termination and of suitable form and situation. For instance, it may be either concentric or eccentric with the axis of the fan or concentric with or more 45 or less eccentric to the inward termination of the throat of the eye.

I will now describe some forms of my invention as applied to a fan-wheel and casing of the type described in my said pending application, Serial No. 229,896, wherein the fan-wheel blades are axially shorter than the width of the casing.

Figure 1 is an elevation, and Fig. 2 is a section of Fig. 1 on the line X Y. Figs. 3 and 4 55 are similar views to Figs. 1 and 2, showing

a modification. Figs. 5 and 6 are similar views of another modification; and Figs. 7, 8, and 9 show further modifications.

Referring to Figs. 1 and 2 as applied to the type of fans referred to, the inner termination or inner end of the throat of the eye a is of circular formation and eccentric to and of smaller diameter than the circle b described by the inner edges of the fan-blades c and is extended inward more or less up to or beyond 60 the plane of the intake ends of the fan-wheel blades c. In the drawings the end a of the eye is shown as extended not quite up to the plane of the fan-wheel blade ends, and it is obvious that if it is extended inward beyond 65 the said plane the boundary a of the eye must not extend beyond the circle b described by the inner edges thereof. The eccentric displacement of the inner termination a of the eye is such as to bring it closest to the 70 circumference of the fan-wheel where the suction thereof is strongest—i. e., in the fan shown in the drawings the displacement will be toward the right-hand side of the figure, as shown, so as to bring one side of the inner 75 termination a coincident with the blades c within or sometimes even without the circle b described by the inner edges thereof. In 80 centrifugal fans inclosed in a snail-shaped casing the position of greatest suction will 85 generally be on the opposite side of the fan-wheel to that part which comes closest to the outer circumference of the casing. The position will, however, be determined by the particular type of fan and casing to which the 90 invention is applied.

The position of the inner termination a of the throat of the eye, as just described, is eccentric to the axis of the fan. The entrance d of the throat is, however, of larger dimensions than the inner termination a and is preferably concentric to the circle b of the fan-wheel blades or the axis of the fan-wheel, in which case the entrance d will coincide 95 more or less with one side of the inner termination of the eye, whereby the wall of the throat at the side e will be substantially at right angles to the plane of revolution of the fan-wheel f and inclined on the other side g, according to the relative dimensions of the 100 entrance d and the inner termination a of the eye. If the larger entrance is concentric with the smaller inner termination, the wall of the throat will of course form a truncated cone, as shown in Figs. 3 and 4, where simi- 105 110

lar letters of reference are used to Figs. 1 and 2, with the exception of that referring to the wall of the throat, which in this case is indicated by the letter *h*.

5 In another form shown in Figs. 5 and 6 the entrance *d* to the throat may be both eccentric to the inner termination *a* and eccentric to the circle of the fan-blades *c*, and as will be apparent from these figures the walls of the 10 throat will be of greater angle on the one side *g* than on the other side *e*. The inner termination *a* of the eye may in some cases be of irregular formation extending inward more on one side than on the other. For instance, in 15 a fan of the type referred to, and as shown in Fig. 6, the wall *g* which is nearest the axis of the fan-wheel may be extended, as at *i*, beyond the plane of the intake ends of the blades, and such extension may be either 20 parallel with the axis of the fan-wheel *f*, as shown in this figure, or it may be in alignment with the angular wall *g*, as shown at *i* in Fig. 7, which otherwise corresponds with Fig. 2. The extension *i* may be of equal 25 depth, or it may gradually fade away, as shown in the drawings, toward the adjoining parts or opposite wall *e*, Fig. 7. The angles and corners may be rounded off by suitable curves. Extensions such as referred to may 30 also be employed with the form of throat shown in Figs. 3 and 4, Figs. 8 and 9 illustrating such constructions.

What I claim as my invention, and desire to secure by Letters Patent, is—

35 1. In a centrifugal fan or pump, a fan-wheel, and an eye leading thereto constructed in the form of a throat, the inner termination thereof being eccentric to the axis of the fan-wheel.

40 2. In a centrifugal fan or pump, a fan-wheel, and an eye leading thereto constructed in the form of a throat, the inner termination thereof being eccentric to the axis of the fan-wheel, and the entrance thereof being concentric with such axis.

45 3. In a centrifugal fan or pump, a fan-wheel, and an eye leading thereto constructed in the form of a throat, the inner termination of said throat being smaller than the entrance thereto, and being eccentric to the axis of the fan-wheel.

50 4. In a centrifugal fan or pump, a fan-wheel, and an eye leading thereto constructed in the form of a throat, the inner termination of said throat being smaller than the entrance thereto, and being eccentric to the axis of the fan-wheel, and the entrance thereof being concentric with such axis.

55 5. In a centrifugal fan or pump, a fan-wheel, and an eye leading thereto constructed in the form of a throat, the inner termination thereof being eccentric to the entrance thereof.

60 6. In a centrifugal fan or pump, a fan-wheel, and an eye leading thereto constructed

in the form of a throat, the inner termination thereof being smaller than its entrance, and being eccentric thereto.

7. In a centrifugal fan or pump, a fan-wheel, and an eye leading thereto constructed 70 in the form of a throat, the inner termination thereof being smaller than its entrance, and being eccentric thereto, and said entrance being concentric with the fan-wheel axis.

8. In a centrifugal fan or pump, a fan-wheel, and an eye leading thereto constructed 75 in the form of a throat, the inner termination thereof being smaller than the circle described by the fan-blades, and eccentric thereto, and the entrance thereof being 80 larger than the said inner termination and concentric with such circle.

9. In a centrifugal fan or pump, a snail-shaped casing, a fan-wheel mounted to rotate therein, and an eye constructed in the 85 form of a throat leading from said casing to said fan-wheel, said throat having its inner termination smaller than its entrance and eccentric to the axis of the fan-wheel.

10. In a centrifugal fan or pump, a snail-shaped casing, a fan-wheel mounted to rotate therein, and an eye constructed in the 90 form of a throat leading from said casing to said fan-wheel, said throat having its inner termination smaller than its entrance and 95 eccentric to the axis of the fan-wheel, and said entrance being concentric to said axis.

11. In a centrifugal fan or pump, a snail-shaped casing, a fan-wheel mounted to rotate therein, and an eye constructed in the 100 form of a throat leading from said casing to said fan-wheel, said throat having its inner termination smaller than its entrance and eccentric to the axis of the fan-wheel, and having its wall on the side which is nearest 105 the fan-blades extended substantially at right angles to the plane of rotation of the fan-wheel, and on the opposite side inclined thereto.

12. In a centrifugal fan or pump, a snail-shaped casing, a fan-wheel mounted to rotate therein, said fan-wheel being formed of blades of a length materially less than the depth of the casing, whereby there is left a space between the casing and the fan-wheel 115 at the intake end of the latter, and an eye constructed in the form of a throat extending inwardly from said casing across said space, said throat having its inner termination smaller than its entrance and eccentric to the 120 axis of the fan-wheel.

13. In a centrifugal fan or pump, a snail-shaped casing, a fan-wheel mounted to rotate therein, said fan-wheel being formed of blades of a length materially less than the depth of the casing, whereby there is left a space between the casing and the fan-wheel 125 at the intake end of the latter, and an eye constructed in the form of a throat extending inwardly from said casing across said space, 130

said throat having its inner termination smaller than its entrance and eccentric to the axis of the fan-wheel, the side of such inner termination which is nearest such axis being 5 extended into the fan-wheel to a point beyond the plane of the intake ends of the blades.

In witness whereof I have hereunto signed my name in the presence of two subscribing witnesses.

SAMUEL CLELAND DAVIDSON.
